UNITED STATES PATENT OFFICE.

CHARLES JOB FOOKS, OF EALING, ENGLAND.

CASEMENT-STAY FOR WINDOWS.

SPECIFICATION forming part of Letters Patent No. 762,296, dated June 14, 1904.

Application filed September 11, 1903. Serial No. 172,837. (No model.)

To all whom it may concern:

Be it known that I, CHARLES JOB Fooks, a subject of the King of Great Britain, residing at 31 Warwick road, Ealing, in the county of 5 Middlesex, England, have invented new and useful Improvements in Casement-Stays for Windows, of which the following is a specification.

My invention relates to improvements in 10 casement-stays for windows. I attain these objects by the mechanism illustrated in the accompanying drawings, in which—

Figure 1 is a front elevation of casement-stay fitted to the window and window-frame. 15 Fig. 2 is a plan of Fig. 1.

This invention is constructed with a perforated flat iron stay *a*, rounded at one end *b*, with a thumb-piece to form the handle *c*, and at the other end is a sunk well *d*, cut in the 20 swell *d* with slits *e*, through which a center pin *f* is passed. This said pin is riveted to the swell *d* and operates in two slots *g* in two lugs *h*, cast on a perforated back plate *i*. The back plate *i* is provided with countersunk screw-holes for fixing the same to a window *j* mul- 25 lion sash or frame.

A running perforated block *k* is passed over the stay *a*, the said block being provided with a screwed set-pin *l*. The perforated block is 30 loosely riveted to a back plate *m*. This said back plate is provided with countersunk screw-holes for fixing the plate to a window-sill *n* or frame and the like. Thus the stay connects the window to the window-frame and is fixed

in any position by means of the set-screw before described. 35

The end of the stay has the corners removed or is rounded off as required and slides in a slot cut in the block *o*, which is screwed to the frame. 40

A plate *p*, screwed to the window *j*, is turned up at right angles and is provided with a slot *q*, through which the stay *a* passes from left to right in order to open the window when it is set by means of the set-pin *l* in one of 45 the holes or countersinks *r*.

A center or guide pin *s* is fixed to the top lug *h*, with the lower end of the pin *s* passing into a well *d'*, cut in the top of the swell *d* to act as a stop against the slit *e*. 50

What I claim as my invention, and desire to secure by Letters Patent, is—

In casement-stays for windows, the combination of the flat stay *a* end *b* thumb-piece *c* sunk well *d* swell *d* slits *e* center pin *f* slots *g* lugs *h* block *k* set-screw *l* back plate *m* block *o* plate *p* slot *q* holes or countersinks *r* and center or guide pin *s*, substantially as herein described and according to the accompanying drawings. 55

In testimony whereof I have signed my name to this specification in the presence of two subscribing witnesses.

CHARLES JOB FOOKS.
